UNITED STATES PATENT OFFICE.

ADOLPHE BESSAT AND LÉON LOUIS LIÉVENS, OF NANTERRE, FRANCE.

DUPLICATING APPARATUS.

Application filed September 21, 1922. Serial No. 589,693.

To all whom it may concern:

Be it known that we, ADOLPHE BESSAT, a citizen of the Republic of France, and a resident of Nanterre, France, and LÉON LOUIS LIÉVENS, a citizen of the Republic of France, and a resident of Nanterre, France, have invented a new and useful Duplicating Apparatus, which improvements are fully set forth in the following specification.

10 In order to make our invention more clearly understood, we have appended hereto drawings illustrating by way of example a complete rotary duplicator embodying our invention.

15 In the said drawings:

Figure 1 is an elevation of a machine built according to our invention.

Figure 2 is a section of the same.

20 Figure 3 shows the interior of one of the printing cylinders, and illustrates the arrangement of the kneading rollers fed from a central ink container and forcing ink through the perforated screens of the printing cylinders.

25 Figures 4 and 5 show in section the central ink container in its two positions, "closed" and "open."

Figure 6 is a side elevation of the adjustable device for drying the sheet after it has 30 been printed on its front or back by the second cylinder.

Figure 7 is a face view of the same device.

35 Figures 8 and 9 are face and sectional views of the device for adjusting the relative positions of portions of the impression for printing in two colours or printing on both sides of the paper.

40 Figure 10 is an elevation of a smaller apparatus designed for printing on the front side of the paper only.

Figure 11 illustrates a device designed to secure the blotting paper on the drying rollers.

45 Figure 12 is a section of the device for automatically feeding the paper.

Figure 13 is a plan of the said automatic feeder.

50 Figures 14 and 15 show in section and in front elevation additional parts for the automatic feeding of double sheets.

Our apparatus (Figures 1 and 2) comprises two main parts, namely, two printing cylinders 1 and 2, which are interchangeable and constituted as follows:

55 A perforated screen 3 is mounted on two

rings 4 and 5 secured to two supports 6 and 7 which are mounted in their turn on a fixed hollow axle 8 whereon said supports are rotated by hereinafter described mechanical means.

Inside the said fixed hollow axle 8 is rotatably fitted a tube 9 in which is stored the ink for the printing. This ink-containing tube is closed at two points in its length by fixed and removable plugs 10 and 11, the latter plug enabling the tube to be readily cleaned.

At one end of tube 9 is a milled or knurled stud 12, by turning which the said tube can be rotated within and relatively to axle 8, whereby two slots 13 and 14 (Figures 4 and 5) provided in said tube and axle 8 are made to coincide, thereby permitting the ink contained in the tube to be discharged. Figure 4 shows the containing tube 9 closed and Figure 5 shows it open.

In order to fill the ink container 9, a milled stud 12 has only to be pulled outward, thus withdrawing it from the hollow axle, whereupon the ink can be introduced through the slot 13 which is then at the top of the container (Figure 4). By pushing in the milled stud the ink container is restored to its normal position.

A small arrow, hand, or pointer 15, secured on milled stud 12 shows whether the ink container is closed or open.

Inside the printing cylinders 1 and 2, there is secured to each end of axle 8 a supporting arm or bracket 16, the two brackets 90 jointly carrying three kneading rollers.

The first roller 17 is supplied with ink directly from the ink container. It is mounted at opposite ends on movable blocks 18 which fit adjustably in slots in the brackets 16, thus permitting it to be shifted toward or from the inking device so as to regulate the feed of the ink. It can be held in adjusted position by means of screws 19 and 20 which engage said blocks 18.

Said roller 17 transmits the ink, while kneading it, to roller 21 which is in contact with screen 3, through an intermediate roller 22; these two rollers 21 and 22 are mounted on levers 23 and 24 which are pivoted to brackets 16 and are subjected to the action of suitable springs which tend to maintain said rollers in contact with each other and with the roller 17 and screen 3 despite any oscillations that may occur during rotation.

The ink supplied to the screen in the above explained manner is fed to a fabric wound around the screen and secured by a stretching device hooked to four studs 25; and this fabric, in turn, feeds the ink to the stencil to be reproduced, which stencil is wound around it and held in place by said studs, but it will be apparent that the fabric can be omitted, if desired, and the stencil wound directly around the screen and retained in place by the studs.

Axes 8, carrying the two above described printing cylinders 1 and 2, are mounted on a frame 26 and secured by clamping devices 27 and 28; these devices are mounted on pivots 29 and are held in place by milled studs 30.

Proper positioning of the cylinder-carrier axles in frame 26 is ensured by lugs 31.

A pair of cams 32 mounted on a shaft 33 operated by a handle 34 act on the lower arms of a pair of centrally-pivoted levers 35 which are subjected to the action of retractile springs 36. These cams oppose the action of springs 36 and in so doing cause pressure roller 37 to be kept away from the printing cylinder during the starting period.

In the case of printing cylinder 2, the separation of the corresponding pressure roller 40 therefrom is effected in the following manner:

Lever 38 has a two-fold function in that it is intended to effect the imposition of pressure, as the case may be, either on or under the printing cylinder according to the position it occupies for colour printing or printing on both sides of the paper, which position will be hereinafter described.

For this purpose, spring 39, which causes roller 40 to press on printing cylinder 2 is connected to an operating handle 41, which can shift spring 39 to the right or to the left, thus changing the direction of the pressure. This operation therefore also withdraws pressure roller 40 from cylinder 2 during the starting period.

Handle 41 is kept in proper position by means of a detent 42 (Fig. 2) which engages the adjacent part of frame 26 and is preferably subjected to the action of a spring concealed in said handle. The latter is connected by shaft 44 to a similar crank or handle at the opposite side of the machine and to which a similar spring 43 is attached, so that both springs 39 and 43 will thus be shifted in unison. Spring 43 acts on a lever 38 at the same side of the machine, and this last-named lever 38 acts conjointly with the front lever on the pressure roller 40.

Rotation of the parts of the machine (Figures 1 and 2) is effected by crank 45 which operates a train of pinions shown in dot-and-dash lines. Should a power or electric drive be used, the crank would be replaced by any suitable transmission gear.

When the machine is in operation for

simultaneous printing on both sides of the paper, printing cylinder 1, by means of the rollers 46 and 47, which is carries, lowers the levers 35, thus moving the rubber pressure roller 37 away from said cylinder. 70

This lowering action is effected by providing the upper arms of the levers 35 with vertical extensions 35' which are formed at their free ends with cams 35"; said cams being disposed in the path of the rollers 46 75 and 47 so as to be engaged thereby. The levers 35 are thus rocked in a clockwise direction, with the result that the roller 37 is carried away from cylinder 1; the space between said roller 37 and the cylinder permitting the studs 25 on the latter to pass therethrough and enabling the sheet delivered by the hereinafter-described feed table to be brought to the precise position where it can be engaged by roller 37 as soon as 85 that roller is again raised into contact with said cylinder.

The sheet is thus driven and printed.

Then, led by a guide-plate 48, it passes between the two rollers 49 and 50. Roller 49 drives roller 50 which is a blotter for drying the front side of the paper; said roller 50 is mounted on a bell-crank lever 51 which, through spring 52, ensures the required pressure on driving roller 49. 95

While the sheet is passing under drying roller 50, cylinder 2 lifts roller 40 by means of its rollers 53 which operate levers 38, thus permitting the already front-printed sheet to be positioned at the exact place whence, as soon as a roller 40 is lowered, it will continue to be driven, so as to be printed on the back. 100

After being printed on the back, the sheet continues its travel, passes through the hereinafter described drying device (Figure 6) and drops on a receiver tray hooked to the latter.

When the apparatus is in operation for simultaneous printing in two colours, printing cylinder 2 has to be positioned as shown by dotted lines in Figure 1, and roller 40 is to be put on the lower supports 54 on levers 38. It is to be understood in this connection that the said levers 38 are, in part, of duplex construction: that is to say, the upper arms have upper and lower extensions 38' at their ends, as shown in dotted lines in Figure 1, each extension being provided with a terminal cam 38"; so that in either position of cylinder 2 its studs or rollers 53 will engage the adjacent cams during the revolution of the cylinder. 110

Both cylinders 1 and 2 are therefore in the same plane. 125

Each of them is fitted with an original stencil, one for the fundamental or ground print colour, the other for the complementary colour, and, of course, the two ink containers are filled with differently coloured inks. 130

In order to permit perfect relative adjustment of portions of the impressions for two-colour printing as well as for printing on both sides of the paper, we provide an 5 adjusting device (Figures 8 and 9). This device, by means of screw 55 and of ring 56 secured to pinion 57, enables the latter to be rendered independent of support 58, thus enabling said support to be turned or shifted 10 either forward or backward, as required for adjustment. The extent of this shifting is limited by notch 59 in support 58. Once the adjustment is completed, support 58 is again made fast to pinion 57 by tightening screw 55.

After having been printed on its under side by cylinder 2, the two-colour printed sheet continues its travel and passes through 20 the drying device which we will now describe.

Led by guide-plate 60, the sheet passes between driving roller 61 and blotting roller 62 and thence drops on the receiver tray.

Rotation of the driving device is obtained 25 as follows:

Pinion 63 (Fig. 6) meshes with and is driven by pinion 64 which is itself rotated by the aforementioned driving train operated by handle 45. Said pinion 63 meshes 30 with and drives pinion 65 which, in turn, drives pinion 66, the latter driving a pinion 67 fixed to driving roller 61.

For drying the sheet in the case of both-side printing, drying roller 62 must pass 35 under roller 61.

This is operated as follows: The two rollers 61 and 62 are mounted in a movable frame 68 adapted to swing about two pivots 69 and 70. Said frame is provided with 40 two tightening studs 71 and 72 adapted to keep it in the required position, and these two studs 71 and 72 have only to be shifted from notch 73 to notch 74 and vice-versa.

When the swinging frame is turned over, 45 pinion 67 of driving roller 61 comes into mesh with pinion 65 permitting rotation in the opposite direction and guide-plate 75 takes the place of guide-plate 60.

The whole drying device is detachable, 50 swings about its hinges 76, to allow cylinder 2 to be removed when required, and is secured to the machine by two hooks 77 (Figure 6).

To permit prompt and easy replacement, 55 each drying roller 50 and 62 is detachably mounted on its axle whereon it is held on one side by a cheek or flange 78 (Fig. 7) provided with a journal 79 and on the other side by a tightening ring 80 screwed on axle 81, thus ensuring at the same time the fixing and the drive thereof.

A simple means for fixing the blotter on 60 the drying roller (Figure 11) consists in forming the roller with a longitudinal slot 83 in which a metal blade 84 is set to secure

the strip of blotting paper, which strip is constantly stretched by means of a spring hook 85.

As already stated, the apparatus is provided with an automatic paper feeding device (Figures 12, 13, 14 and 15) constituted by a plate or table 86, on the sides of which are secured two rails 87 and 88.

Said table 86 is secured to the machine 75 in the following manner:

The rails are provided in front with two slots 89 to receive a cross-shaft 90 which is securely held therein by a V-shaped strut 91 pivoted at the upper ends of its arms to the under side of the table and 80 fixed at its apex to the bed of the machine by means of a milled or knurled stud 92.

In view of enabling paper of different sizes to be used, two paper-guides 93 and 94 are arranged on the sides of rails 87 85 and 88 and operated by means of milled studs 95 and 96 controlling two set or adjustment screws 97 and 98. Transversely of the table and at the rear thereof is another paper guide 99 operated by a screw 90 100 working in slot 101 provided in plate 86.

In front, the sheets 102 are stopped by a stop 103 sliding in grooves 104 made in the front part of the two rails 87 and 88. On top of said stop 103 are let in two blades 95 105 holding the sheets to be printed and permitting stop 103 to be maintained always at their level.

To the said stop are affixed two pins 106 100 on which rests a guide-shutter 107 linked on a small axle 108 journaled on the ends of rails 87 and 88. Said pins allow guide-shutter 107 to follow the downward movement of stop 103 and thus to be kept constantly in the position required for guiding the sheets to be printed down to roller 37 (Figures 1 and 2).

Working of the automatic feeder is as follows:

A pinion 109 is provided with a stud 110 110 to which is pivoted one end of a connecting rod 111 locked there by a bolt 112 operated by a pull knob 113.

Said connecting rod transmits the required reciprocatory motion to two arms 114 115 and 115 attached to an axle 116 journaled in two bearings 117 secured under table 86.

At the upper part of these two arms are provided two guide notches 118, so as to reciprocate shaft 119 in slots 120 formed in 120 the rails 87 and 88.

Said shaft 119 has pivoted to it two arms 121 and 122, carrying rubber roller 123.

On the apparatus being operated, a stop 124 on a counter-arm 125, which is associated with arm 121, comes into contact with rod 126 which connects the two rails, thus locking the said counter-arm 125 for a moment against movement. This arm 125 is provided with two slots 128 and 127, which 130

allow shaft 119 and arm 121 to continue their travel. A pawl 129 is carried by arm 121 and is normally engaged by arm 125 and held in inoperative position; but when 5 said arm 121 moves beyond arm 125, the said pawl is released and, under the action of a coil spring 130, comes into engagement with ratchet 131, thus locking roller 123 against rotation for an instant. Hence said 10 roller, in its rearward movement will carry with it the sheet held by paper guide 99, thus causing the sheet to buckle with the result that the said sheet is disengaged from the two blades 105 of stop 103.

15 At this moment roller 123 resumes its movement in the opposite direction and, on being blocked for a second time by pawl 134 acting on ratchet 135, it travels nine centimeters, the first two of which permit the 20 parts of counter arm 125 and its associated parts to be returned to position by spring 136.

While effecting its 9-centimeter travel, roller 123 takes with it the sheet to be 25 printed which, passing above blades 105 and shutter-guide 107 is brought on roller 37 to be driven by the latter when the said roller 37 comes again into contact with printing cylinder 1.

30 For feeding a new sheet, roller 123 rolls back freely until counter-arm 125 and its parts become operative again.

For automatic feeding double sheets (Figures 14 and 15) a removable cambered tablet or leaf 137 is positioned transversely of table 86 and secured thereto by two pins 138. The purpose of this tablet is to initiate the bending 133 of the sheets, which bending is completed by the action of a heavy balance-weight bar 132 descending in grooves 139 40 of paper guide 99, wherein it is held by two studs 140.

A sheet counter 141 (Figure 13) is mounted on the side of the automatic feeder and 45 actuated from arm 115 by a connecting rod 142.

The apparatus hereinabove described may be used as single operating, that is to say, for printing only the front side of a sheet of 50 paper by means of cylinder 1. For this purpose, all that has to be done is, after removing cylinder 2, pressure-roller 40, and the complete drying device (Figure 6) to hook the receiver-tray on support 82 of 55 guide-plate 48.

Figure 10 illustrates an apparatus adapted for printing on one side of the paper only.

Having now particularly described and 60 ascertained the nature of our said invention and in what manner the same is to be performed, we declare that what we claim is:

1. In a duplicating apparatus, a stationary, hollow axle having a slot in its lower 65 surface; a hollow printing cylinder loosely

mounted on said axle; means for rotating said cylinder; an inking device disposed within said cylinder to supply ink to the surface thereof, and connected to said axle to be supported thereby; and an ink-containing tube rotatably fitted within the axle and having a slot which is normally out of registration with the axle slot but is adapted to be brought into registration by the rotation of the tube to feed the ink to said 70 inking device.

2. In a duplicating apparatus, a stationary, hollow axle having a slot in its lower surface; a hollow printing cylinder loosely mounted on said axle; means for rotating 80 said cylinder; an inking device disposed within said cylinder to supply ink to the surface thereof, and connected to said axle to be supported thereby; and an ink-containing tube removably and rotatably fitted within the axle and having a slot which is normally disposed in the upper portion thereof, said tube adapted to be withdrawn through one end of the axle to be filled with ink through its slot, and thereafter to 85 be moved back into said axle and rotated so as to bring said slot into registration with the axle slot to feed the ink to said inking device.

3. In a duplicating apparatus, a stationary, hollow axle adapted to contain ink; a hollow printing cylinder loosely mounted thereon; an inking device disposed within the cylinder to supply ink to the surface 95 thereof, and connected to the axle to be supported thereby; a member within the axle 100 movable manually at will into and out of position to feed ink from said axle to the inking device; and means for rotating the cylinder on said axle.

4. In a duplicating apparatus, a stationary hollow axle having a slot in its lower surface; a hollow printing cylinder loosely mounted on, and rotatable relatively to, said axle; an inking device disposed within the cylinder and comprising a supporting frame suspended from the axle and a train of rollers carried by said frame and leading from the axle slot to the surface of the cylinder; and an ink-containing tube rotatably 110 fitted within the axle and having a slot which is normally out of registration with said axle slot but is adapted to be brought into registration by the rotation of the tube to feed the ink from said tube to the adjacent roller of the inking device.

5. In a duplicating apparatus, the combination of a printing cylinder; a pressure roller coacting therewith; a pivotally-mounted carrier for said roller; spring 125 means connected with said carrier to normally hold the same in a position in which the roller is pressed against the cylinder; and a stud on said cylinder engageable directly and positively with said carrier at 130

- regular intervals during the rotation of the cylinder to rock the carrier out of such position and thereby move the roller away from said cylinder.
- 5 6. In a duplicating apparatus, the combination of a printing cylinder; a pressure roller coacting therewith; pivotally-mounted supporting means for said roller; spring means connected with said supporting means 10 to normally hold the roller against the cylinder; a member on said cylinder engageable periodically with said supporting means during the rotation of the cylinder to automatically move the roller away from the cylinder; and a manual device operable at will on said supporting means to move said roller away from said cylinder.
- 15 7. In a duplicating apparatus, a stationary, hollow axle; a hollow printing cylinder loosely mounted thereon; an inking device within the cylinder to supply ink to the surface thereof, and connected to said axle to be supported thereby; an ink-containing tube movably fitted within the axle, said tube and axle having cooperating means for feeding ink to said inking device consequent upon the movement of the tube; and means for rotating the cylinder on said axle.
- 20 8. In a duplicating apparatus, a stationary, hollow axle; a hollow printing cylinder loosely mounted thereon; an inking device within the cylinder comprising a pair of brackets suspended from the axle, pairs of 25 spring-pressed levers pivoted to the brackets, and a train of rollers leading from the axle to the surface of the cylinder and embodying a roller adjustably mounted in said brackets to move toward or from said axle, and other rollers journaled in said pairs of levers and held by the spring pressure in contact with each other and with the first-
- named roller and the cylinder surface; means for feeding ink from the axle to said first-named roller; and means for rotating the cylinder on said axle.
- 45 9. In a duplicating apparatus, the combination of a printing cylinder; a pressure roller coacting therewith; a pair of pivotally-mounted levers disposed at opposite ends of said roller and provided at one side of their fulcra with supports wherein the roller ends are engaged, and also with extensions having terminal cams; spring means connected with said levers to normally hold them in a position in which the roller is pressed against the cylinder; and projections on the cylinder ends engageable directly and positively with said cams at regular intervals during the rotation of the cylinder to rock the levers out of such position and thereby move the roller away from said cylinder.
- 50 10. A duplicating apparatus, according to claim 9, in which the printing cylinder is movable at will between a position for printing on one side of a sheet and a position for printing on the other side; and in which the levers are provided with duplex roller supports and cam extensions disposed at opposite sides of the sheet, so that the roller may be supported in position to be moved away from the cylinder by the coaction between the cylinder projection and the adjacent cams in either position of the cylinder.
- 55 60 70 75
- In testimony whereof we have signed this specification in the presence of the subscribing witness.
